UNITED STATES PATENT OFFICE.

JOHN J. A. MILLER, OF DENVER, COLORADO, ASSIGNOR TO THE AUTOMATIC FURNACE OXIDATOR AND MANUFACTURING COMPANY, OF DENVER, COLORADO, A CORPORATION OF COLORADO.

LIQUID-CONTROLLED GRAVITY VALVE FOR USE WITH FURNACE OXIDATORS AND MECHANISM FOR OPERATING THE SAME.

Application filed January 15, 1923. Serial No. 612,790.

To all whom it may concern:

Be it known that I, JOHN J. A. MILLER, a citizen of the United States of America, residing at the city and county of Denver and State of Colorado, have invented new and useful Liquid-Controlled Gravity Valves for Use with Furnace Oxidators and Mechanism for Operating the Same, of which the following is a specification.

10 My invention relates to improvements in liquid controlled gravity valves for use with furnace oxidators and mechanism for operating the same, and particularly to valves of this character which are employed in closing 15 the air inlet dampers of furnace doors at a predetermined time after the said damper has been opened.

The object of my present invention is to provide a valve which is adapted to be either 20 automatically or manually raised when the furnace door is opened to coal the fire of a steam generating boiler, and which will then drop slowly by gravity through a body of suitable liquid, preferably oil, within a predetermined period of time after the door is 25 closed, varying from about two to six minutes, means being provided for determining the rapidity of the drop of said valve.

Further, to provide an oil controlled gravity valve comprising an oil holding cylinder, and a piston therein having a rod or rods adapted to be connected to an object to impart movement thereto, said piston having an opening extending through the same, and 35 an adjustable valve for nearly closing said opening, said valve being moved away from the opening on the up stroke of the piston, by the pressure of oil from above, and spring actuated in a counter direction to the descent 40 of the piston, whereby the said valve is moved toward and close to the opening in the piston, on the down stroke of the same, thus controlling the flow of the oil through the piston and thereby retarding its descent, 45 the upper head or cap of the said oil cylinder being concavo-convex, and provided with apertures, which permit oil carried through the cap by the piston rod to flow back into the cylinder.

50 The valve hereinafter described may be used for any purpose for which it is adapted, and in order to show one way in which it may be applied, I have illustrated it as form-

ing part of the mechanism for closing the air inlet damper of a furnace door. 55

In the accompanying drawings:

Figure 1 is a front elevation of a furnace door having an air inlet pipe and a damper therein, showing the application of the improved oil valve as a means of closing the 60 said damper after the door is closed, mechanism being shown for automatically opening the damper when the door is opened.

Fig. 2 is a horizontal sectional view on the line 2—2 of Figure 1. 65

Fig. 3 is a side elevation of Figure 1.

Fig. 4 is a vertical, sectional view—enlarged—of the improved oil controlled gravity valve, the piston being connected by a single piston rod with the rack by which the 70 piston is lifted.

Fig. 5 is a front view of a part of a door equipped in a similar manner to that shown in Figure 1, the valve cylinder being in section, and showing the piston connected by a pair of rods to rack by which piston is lifted. 75

Fig. 6 is a side elevation of Figure 5.

Fig. 7 is a front view of the air preheater 80 shown in Figures 3 and 6.

Fig. 8 is a front view, similar to Figure 1, but showing manually operated means for lifting the piston valve.

Fig. 9 is an enlarged side view of Figure 8, the preheater being removed. 85

Fig. 10 is a side view, partly in section, showing the manner of securing the oil cylinder to a bracket on the furnace door.

Fig. 11 is a plan view of the piston.

Fig. 12 is a plan view of the disk valve 90 which controls the flow of oil through the piston, and

Fig. 13 is a sectional view showing the valve cylinder, the piston therein, and its operating mechanism, and a housing integral 95 with said cylinder for enclosing said mechanism.

Referring to the accompanying drawings:

The numeral 1 indicates a furnace door, and 2, an air pipe extending through the same, having a transverse damper rod 3, to which is secured a damper 4. The damper rod 3 extends beyond one side of the air pipe 2 to a point slightly beyond the hinged edge of the door; and this end of the rod 100 carries a tappet 5, this end portion of the

105

rod being supported in a bearing 6 which is bolted to the furnace door.

Upon the hinge pin 7 of the door is secured a horizontal plate 8 having a hub 5 through which the pin passes, and which is secured to the pin by a set screw 9, the back edge of the plate engaging the door and thereby preventing turning of the plate upon the pin. The plate has a projecting portion 10 which is positioned to stand in the path of the upper end of the tappet 5, and when the door is opened, the tappet strikes the edge of the projection 10 and is thereby swung downward at an angle of about forty-five degrees, thereby turning the damper rod and swinging the damper from a vertical or closed position to a horizontal or open position. As long as the door remains open, the tappet is held in a depressed position by the plate 8, but when the door is closed, the tappet passes out from under the plate, thus permitting the damper to be closed by the improved oil controlled gravity valve, as will be hereinafter set forth.

25 The damper rod 3 has rigidly mounted thereon adjacent the pipe 2, a toothed segment 11, which operates to lift the improved oil controlled valve, in a manner to be presently set forth.

30 The parts thus far mentioned show the manner in which a furnace door air inlet damper may be automatically opened, the closing of the damper being effected by the improved valve, which is constructed and arranged in the following manner: The improved oil controlled gravity valve comprises a cylinder 12, having heads or caps 13 and 14 provided with annular bosses 15, which fit in the respective ends of the cylinder, and the caps are held in place by headed rods 16, which pass through holes in the caps, the ends of the rods being threaded to receive clamp nuts 17, which are screwed against the adjacent cap.

35 The upper cap 13 is concavo-convex in form and is provided with an axial piston rod hole, and surrounding this hole are a number of small drain holes 18. The concavo-convex form of the cap 13 enables it to catch any oil which works through the axial piston rod hole, and this oil drips back into the cylinder through the holes 18, thus avoiding waste.

40 The lower cylinder cap 14 may be so constructed as to enable it to be secured to any form of support made necessary by the use to which the valve is put. In the present instance, the cap 14 is formed with a central depending circular lug 19 having a threaded axial hole 20, and this lug fits into a socket 21 on a shelf 22 of a bracket 23, which is secured to the furnace door. The socket is preferably of slightly less depth than the length of the lug 19, and a bolt 24 is passed loosely through a hole in the shelf, and

screwed into the hole 20 in the lug until the head of the bolt is clamped tightly against the shelf, thereby tightly clamping the end of the lug against the bottom of the socket, by which the cylinder is firmly secured to the shelf.

45 Within the cylinder is placed a piston 25, which is of the form shown clearly in Figures 4 and 11, and comprises a hollow cylindrical portion having a bottom wall provided with a central hole 26, the upper end of the piston consisting simply of a central hub 27, which is integrally connected to the surrounding piston wall by spider arms 28.

50 The hub 27 is provided with a central threaded aperture 29 and the hub is counterbored from its upper end, as shown at 30, and in the counterbore is secured the lower end of a hollow piston rod 31, which extends out through the axial hole in the cylinder cap 13, a distance sufficient for the purpose for which it is intended, and upon the upper end of this piston rod is secured a member 32 having a central aperture 33 of slightly less diameter than the internal diameter of the hollow piston rod, and the lower end of the member 32 is counterbored for a suitable depth to receive the upper end of the piston rod, the opposite ends of the piston rod being secured to these respective counterbores by pins 34, which pass through the piston hub 27 and member 32, respectively, and through recesses in the periphery of the piston rod, as clearly shown in Figure 4.

55 A stem 35, which fits snugly but rotatably in the aperture of the member 32 is passed down through the said member and through the hollow piston, the lower portion of the stem being threaded and screwed through the threaded aperture 29 in the piston hub. The threaded portion of the stem terminates approximately a half inch from the extremity of the stem, and this latter portion 36 is of slightly less diameter than the remainder of the stem, thereby forming a shoulder 37. The reduced portion 36 is unthreaded, and a disk valve 38 having an axial hole 39 is mounted in this reduced portion, and is normally held against the shoulder 37 by a spiral coil spring 39, which surrounds the reduced portion and is held under tension against the disk valve by a pin 40 in the lower end of the stem. Upon

60 the upper end of the stem 35 is secured a knurled thumb nut 41, by turning which the stem may be moved up or down through the threaded hole 29 in the piston hub, for a purpose to be presently described. The member 32 on the upper end of the hollow piston rod is adapted to be connected with some mechanism to which it is desired to impart movement, the form of connection depending upon the character of the mechanism. In the present case, the purpose of the valve is to impart a quarter turn to the

damper rod 3, and for this purpose the member 32 is provided with rack teeth 42, which mesh with the teeth of the segment 11 on the said damper rod 3. When the furnace door is opened, the tappet 5 is engaged by the plate 8, as previously described, thereby turning the damper rod together with the damper 4 and segment 11. This movement of the segment raises the piston rod and its piston, and when the tappet is released from the plate 8 by the closing of the furnace door, the segment 11 is swung slowly down again to its normal position, by the gravity drop of the piston.

15 The member 32 is held in engagement with the segment 11 by a roller 33, which is mounted on a bracket 38, which is adjustably secured to the adjacent side of the air pipe 2, the said roller bearing against the opposite edge of the member 32 from its toothed edge.

The cylinder 12 may be simply an air cylinder, but is preferably supplied with a suitable liquid, oil being preferred, to retard the descent of the piston, the time required for the piston to drop from its highest to its lowest position being determined by the nearness of the disk valve 38, to the bottom of the piston, by which the flow of oil through the hole 26 in the bottom of the piston is regulated, and the position of the disk with respect to the hole 26 is determined by adjusting the stem 35. When the piston rod and its piston is raised in the manner above described, or by any other means, the oil above the piston passes through the hole 26 in the bottom of the piston, and out over the circumferential edge of the disk valve 38, which is of less diameter than the piston, the valve being forced away far enough from the bottom of the piston by pressure of the oil, and against the pressure of the spring 39, to permit the free passage of the oil through the said hole 26.

45 The instant the piston begins to drop by gravity, the disk valve 38, under the combined pressure of the oil and the tension of the spring 39 is forced up against the shoulder 37 of the stem 35, by which the space between the disk and the bottom of the piston is defined, and the downward pressure on the oil by the piston and its disk valve forces the oil up between the disk and the bottom of the piston and through the hole 26, and thus the piston is permitted slowly to descend, the time required for its descent to the bottom of the cylinder being determined by the space between the bottom of the piston and the disk. As the piston descends, the segment 11 is thereby turned to its normal position, by which the damper is closed.

50 In Figures 5 and 6 is shown a construction in which the hollow axial piston rod 31

is dispensed with, and in its place I employ a pair of rods 42, which are bolted at their lower ends to the hub of the piston, and at their upper ends to opposite sides of the lower end portion of the toothed member 32, the mechanism in all other respects being precisely the same as above described. The rods 42 are preferably flat rods and pass through corresponding slots in the upper cylinder cap 13.

75 The inner end portion of the pipe 2 is threaded to a ring portion 1^a of the bracket 23, and extends a short distance beyond the inner face of the door, and upon the inner end portion of the said pipe is screwed an air preheater of the style clearly shown in Figures 3, 5 and 6, and consisting of a flaring metal band, 43, and an axial tubular member 44, which are integrally connected by radial blades 45, which alternate with radial blades 46, which terminate short of the tubular member 44, the inner end of the preheater being internally threaded to engage the threaded end of the pipe 2.

90 In Figures 8 and 9, I have illustrated the same adaptation of the improved oil controlled valve, that is, its use in connection with a furnace door damper, but in these views I illustrate means for manually lifting the piston as follows: In this arrangement, the damper rod 3 extends only a slight distance beyond one side of the air pipe 2, and on this extended portion is secured a toothed segment 47, from which projects a stem-like tappet 48, the outer end of which lies in the bifurcated end 49 of a vertically disposed arm 50, the lower end of which is pivotally attached to an inverted L-shaped lever 51, at the intersection of the vertically disposed portion of said lever with its horizontally disposed portion, the free end of the latter member of said lever being pivotally connected to ears 52 on the bracket 23, which is suitably secured to the furnace door.

95 The lower end of the lever 51 terminates in a hand hold member 53, and the pivoted end of the lever is formed with oppositely disposed lugs 54 having threaded apertures in which are screwed stop bolts 55 and 56, the latter bolt being adapted to abut against the bracket 23 to define the downward swing of the lever, while the bolt 55 defines the upward swing of the lever, this lever forming the door opening means.

100 When the damper is in a closed position, the tappet 48 on the segment 47 lies in the crotch of the arm 50, and when the door opening lever 51 is raised, the arm 50, which is lifted by said lever, in turn, swings the segment 47 far enough to fully open the damper. This movement of the segment raises the piston rod and its piston, and when the lever 51 is released, it swings down to its normal position, leaving the segment free

to be slowly moved down to its normal position by the gravity drop of the piston.

In Figure 13 is shown a sectional view of a dust proof housing 12^B, having an integral depending oil holding cylinder 12^A, in which is mounted the piston 25. The housing is adapted to be secured to the furnace door, and the damper rod 3 passes through opposite sides of the housing. The segment gear 11, which is secured upon the damper rod, is enclosed within the housing, as is also the toothed rack 32, which meshes with the segment gear and the connection 42 between the said toothed rack and the piston. The housing shields the piston and its valve from dust and grit, and thus enhances the efficiency of the mechanism.

In the present application of the oil valve, the descent of the piston would be so retarded as to admit air to the combustion chamber of the furnace for a definite period after coaling, but for any purpose for which the valve may be employed to effect the movement of a mechanism, the descent of the piston may be regulated to effect the movement of the said mechanism within any required period of time.

Having described my invention, what I claim as new and desire to secure by Letters Patent, is:

1. In an oil controlled gravity valve, an oil holding cylinder, a piston therein having a passage therethrough, a rod extending from said piston, a vertically adjustable stem extending through said rod and passage, a spring actuated valve slidably mounted on said stem below the entrance of said passage, to control the flow of oil through the same, a stop on said stem for defining the closing movement of said valve, means for raising the piston and rod, and means

whereby said rod may be connected with a mechanism for moving the same.

2. In an oil controlled gravity valve, the combination with an oil holding cylinder, a piston therein having a passage therethrough, a hub, and a rod on said piston having a toothed portion, of a stem having a threaded portion which passes through a threaded aperture in said hub, the lower end portion of the stem extending through the piston passage, and being of less diameter than the remainder of the stem to form a shoulder at the junction of the two diameters, a disk valve slidably mounted on the reduced portion of the stem, a coil spring for normally holding said valve against said shoulder, and a knurled thumb nut on the upper end of said stem for adjusting said rod, whereby the distance between said valve and the entrance to the piston passage may be varied.

3. In an oil controlled gravity valve, an oil holding cylinder, a hollow piston therein having a hub provided with a threaded hole, and openings through its opposite ends, a piston rod secured in said hub, having a toothed portion at its upper end, a stem in threaded engagement with the threaded hole in said hub, a sliding valve on the lower portion of said stem for controlling the opening in the lower end of the piston, a stop on the stem, a spring for normally holding said valve in engagement with said stop, and a thumb nut on said stem for adjusting the same to vary the distance between the valve and the bottom of the piston to define the flow of oil through the piston on its gravity stroke, said valve being moved away from the piston by the down flowing oil as the piston is raised.

In testimony whereof I affix my signature.
JOHN J. A. MILLER,
